UNITED STATES PATENT OFFICE.

MATTHEW J. BOGERT, OF DEMAREST, NEW JERSEY.

DESIGN FOR A WOODEN BOX.

SPECIFICATION forming part of Design No. 29,252, dated August 16, 1898.

Application filed July 25, 1898. Serial No. 686,845. Term of patent 7 years.

To all whom it may concern:

Be it known that I, MATTHEW J. BOGERT, a citizen of the United States, residing at Demarest, in the county of Bergen and State of New Jersey, have invented and produced 5 a new and original Design for a Wooden Box, of which the following is a specification.

This invention relates to a new and original design for a wooden box; and it has for 10 its object to provide a design of this character that shall be both useful and ornamental.

The leading feature of the design resides 15 in a cylindrical body provided at one end with a cap having a narrow rim portion and a pair of closely-arranged exterior annular beads at one edge, which project beyond the exterior surface of the cap, said cylindrical body being further provided at the end opposite the cap with a pair of closely-arranged annular 20 beads projecting beyond its exterior surface and at the shoulder for the cap with a single raised exterior annular bead.

In the drawings, Figure 1 is a side view of 25 a wooden box embodying the herein-described design. Fig. 2 is a longitudinal sectional view thereof.

Referring to the drawings, the numeral 1

designates the cylindrical body of the box, having at one end a neck portion 2, at the base of which is formed the shoulder 3, against 30 which fits the edge of the narrow rim portion 4 of the cap 5. The narrow rim portion 4 of the cap is in the same plane as the exterior surface of the body, and at one edge said cap is provided with a pair of closely-arranged 35 exterior raised annular beads 6, corresponding to the pair of raised annular beads 7 at the opposite end of the body. The said body is further provided at the shoulder 3 for the cap with a single exterior annular bead 40 8, and all of said beads 6, 7, and 8 project beyond the plane of the exterior surface of the cap.

What is claimed is—

The design for a wooden box, herein shown 45 and described.

In testimony that I claim the foregoing as my own I have hereto affixed my signature in the presence of two witnesses.

MATTHEW J. BOGERT.
